SELF WINDING WATCH

Raymond Polo, La Chaux-de-Fonds, Switzerland, assignor to Fabriques Movado, La Chaux-de-Fonds, Switzerland, a Swiss firm

Filed Mar. 22, 1961, Ser. No. 97,630

Claims priority, application Switzerland Mar. 30, 1960

1 Claim. (Cl. 58—82)

My invention has for its object a self-winding watch, the winding of which is obtained through a rocking mass and wherein the barrel controls the balance wheel through the agency of a gearing including a sweep seconds gear. According to the present invention, the latter is the only gear of said gearing to be located centrally, said sweep seconds gear and the escape gear being fitted between the pillar plate and a bar carried by the latter while the support of the winding rocking mass and the part of the gearing connecting the latter with the barrel lies above the two last-mentioned gears.

The accompanying drawings illustrate by way of example a preferred embodiment of a watch according to my invention. In said drawings:

FIG. 1 is a diagrammatic plan view of a watch movement of the self-winding type in which the arrangement of radially meshing gears is illustrated.

FIG. 2 is a reduced diagrammatic plan view showing ordinary wheel trains of FIG. 1 connecting the driving barrel to the escape gear.

FIG. 3 is a partial cross-section of FIG. 2 showing the relative axial positions and radial extent of the pillar plate, the train wheel bridge and a bar secured to the pillar plate and spaced axially therefrom.

FIG. 4 is a reduced diagrammatic plan view similar to FIG. 2 and showing the wheel trains of FIG. 1 of the self-winding mechanism connecting the pinion of the eccentric weight to the driving barrel.

FIG. 5 is a partial cross-section of FIG. 4 showing the relative axial position and radial extent of the pillar plate, a part of interconnected superposed bridges, and the bar of FIG. 3.

FIG. 6 is a cross-section of FIG. 1 through line VI—VI of FIG. 1, showing the position of a known winding device relative to the gear trains and bridges of FIGS. 1—5.

The watch illustrated includes a barrel 1 fitted between the pillar plate 8 and the barrel bridge 9; said barrel drives the large driving wheel 2 constituted by the pinion 2a and the wheel 2b; the latter gear drives the third gear 3 which includes a pinion 3a and a wheel 3b; said third wheel 3b drives in its turn the sweep seconds gear 4 including a pinion 4a and a wheel 4b. Lastly the sweep seconds wheel 4b drives the escape gear 5 including a pinion 5a and a wheel 5b which latter cooperates with the pallet fork 6 cooperating in its turn with the balance wheel 7. 11 designates the balance cock. The two gears 2 and 3, carrying the large driving wheel and third wheel are fitted between the pillar plate 8 and the train wheel bridge 10. The sweep seconds and escape gears above which none of the train wheels described hereinabove are located, are fitted between the pillar plate 8 and a bridge 12 secured to the latter and under which the wheel 3b of the third gear 3 also extends.

The automatic winding mechanism includes a secondary frame constituted by two bridges 13 and 14. Bridge 13

2

is secured to the pillar plate by means of screws 13a and 13b, and bridge 14 is secured to bridge 13 by means of screws 14a and 14b (FIGURE 4). The lower bridge 13 extends laterally over bridge 12, further than bridge 14, so as to reach over the sweep seconds wheel. Along the axis of the latter, there is secured to the lateral extension of the bridge 13 and preferably overhanging coaxially with the sweep seconds wheel, a stud 15, around which at least one cylindric jewel 16 fixed to the hub 17 of the oscillating weight may revolve freely. The oscillating weight includes a radial arm 18 and an eccentric counterweight 19. 20 designates a gib holding the hub 17 at the desired height. As shown in FIG. 6 in cross-section through the legs, U-shaped gib 20 is a well known constituent part of a watch and is mounted on the frame thereof. The hub 17 carries teeth 21 meshing with the pinion 22 forming the first gear of the barrel-winding train and controlling in its turn a conventional reversing gear 23 which need not be described with further detail and which provides for the winding of the barrel for both directions of oscillation of the weight 18—19. Said reversing gear includes two gears 24 and 25, the pinion of the gear 25 meshing with the ratchet wheel forming part of the barrel through the agency of an intermediate pinion 25a. Of course, in accordance with a modification which is not illustrated, the stud 15 may be shifted laterally with reference to the axis of the sweep seconds wheel.

The time indicating means arranged underneath the sweep seconds wheel include a sleeve 26 secured to the pillar plate 8 and inside which is revolvably mounted the spindle 27 carrying the sweep seconds hand and gear. Round said sleeve 26 may revolve freely the cannon pinion 28 round which the hour wheel 29 revolves in its turn. 31 is a gear, the pinion 31a of which meshes with the hour wheel 29 while its wheel 31b rigid with said pinion meshes with the cannon pinion 28 and with the pinion 32 fitted with slight friction over the spindle of the large driving gear 2.

33 designates the time setting stem the axis of which extends in parallelism with the pillar plate; said stem is provided at its inner end with a pinion 34 adapted to rotate the pinion 32 through the intermediate gears 35 and 36 mounted for rotation on a small bridge 8a secured to the pillar plate 8. Pinion 32 in turn engages wheel 31b as stated above to drive the cannon pinion 28 and the hour wheel 29 through pinion 31a affixed to wheel 32b.

Whereas in the case of an ordinary sweep seconds movement, the sweep seconds gear and the center gear are superposed, the present embodiment is provided centrally only with the sweep seconds gear and, above the small bridge 12 underneath which are fitted the said sweep seconds and escape gears, there is fitted the spindle 15 for the oscillating weight. The arm 18 of said weight extends above and beyond the movement, which allows giving the eccentric weight 19 a maximum momentum of inertia; in contradistinction, the actual support of said weight and the train connecting the latter with the barrel do not extend beyond the watch movement; this leads to the execution of a movement of a reduced height, wherein however the oscillating weight lies above the train.

What I claim is:

In a self-winding watch, the combination of a sweep seconds gear, a driving barrel extending laterally of said sweep seconds gear, an escape gear, controlled by said

sweep seconds gear and disposed laterally thereof, a balance wheel co-operating with said escape gear, a pillar plate extending underneath said sweep seconds gear and said escape gear, a first bridge rigid with the plate and revolvably carrying the two last-mentioned gears in a space between it and said plate, a winding weight adapted to oscillate round an axis substantially coaxial with the sweep seconds gear and disposed above said plate and first bridge, a train of gears operatively connecting the barrel with the sweep seconds gear and disposed extending laterally thereof, a secondary frame comprising two bridges one over the other secured to said pillar plate and arranged over said first bridge in a horizontal space remaining free between the barrel and the balance wheel, said sweep seconds gear meshing with the escape gear, a stud secured to

the lower one of said two bridges, a winding weight pivotal on said stud and a winding gearing linking said winding weight to said barrel arranged between said two bridges.
